UNITED STATES PATENT OFFICE.

ALPHONSE DE MAN, OF DETROIT, MICHIGAN.

FIRE-RESISTING DOOR AND DOOR-FRAME.

SPECIFICATION forming part of Letters Patent No. 680,912, dated August 20, 1901.

Application filed February 26, 1900. Serial No. 6,518. (No model.)

To all whom it may concern:

Be it known that I, ALPHONSE DE MAN, a citizen of the United States, residing at Detroit, in the county of Wayne and State of Michigan, have invented certain new and useful Improvements in Fire-Resisting Doors and Door-Frames, of which the following is a specification, reference being had therein to the accompanying drawings.

My invention relates more particularly to fireproof doors and door-frames, and is in the nature of an improvement on a prior invention of mine, shown and described in Letters Patent No. 603,442, issued May 3, 1898. The said prior patent is one for a fire-resisting door and door-frame, and comprises, essentially, a wooden core which is insulated or protected from fire by a covering of some fireproof material, such as asbestos, this insulated core being then faced with wood to give the appearance of the ordinary wooden door. The door-frame likewise comprises an insulated wooden core and wooden facing therefor. The structure as a whole is intended to resist the spread of fire in a building for the reason that the facing may be entirely burned off from the door and frame and still leave the insulated cores intact, and the latter are relied upon to prevent the passage of flame from one room to another.

The device just described while useful and efficient in preventing the spread of fire under certain conditions has, nevertheless, its limitations. First of these is from the fact that in order to thoroughly insulate and protect the core some durable material, such as metal, must be employed, and to this it is difficult to secure the wooden facings. Further, as the core must be twice covered, once with the insulating material and again with the facings, the structure is too complex and expensive.

It is the object of my present invention to obtain a simplified construction of fire-resisting structure which has all the advantages of my prior invention and in addition thereto is capable of better resisting the passage of flames, even after the fire has gained considerable headway; and to this end the invention consists in the peculiar construction of a fire-resisting structure comprising a fireproof core which is exteriorly faced with finishing material and, further, in the construc-

tion of said core, which is of such a nature as to permit of readily securing the finishing facings thereto and combines the qualities of perfect incombustibility with lightness, strength, and a certain degree of penetrability.

The invention further consists in the construction of a door and door-frame having cores of the nature described and, further, in the peculiar construction and arrangement of parts as more fully hereinafter described and claimed.

In the drawings, Figure 1 is an elevation, partly in section, of a door and door-frame of my improved construction. Fig. 2 is a horizontal section on line *x x*, Fig. 1.

The fireproof cores which I employ in my structure are preferably of a composite nature. The exact materials and proportions employed in their composition I do not deem essential to my present invention, as it is obvious that various materials may be employed which will serve the purpose equally well. The essential characteristics of this core are, first, that it will be fire-resisting and non-combustible; second, that it has a surface to which the wooden facing may be secured by gluing, and, third, that it be sufficiently penetrable to admit of securing the facings and hinges or other hardware thereto by nails or screws and also sufficiently tenacious and elastic to hold the said screws or nails. Such a material may be obtained by employing sawdust, wood, or asbestos fiber or other light body material mixed with a sufficient quantity of mineral matter to render the mass non-combustible and a cement for binding the material together and imparting to it a sufficient hardness and strength. The cement of mineral matter which I preferably employ is oxychlorid cement, being composed of a mixture of metallic oxid and a metallic chlorid—such, for instance, as oxid and chlorid of magnesia. This material will render the sawdust or wood fiber non-combustible and will at the same time so firmly bind it together as to form a tenacious material. In compounding the mixture the oxychlorid is mixed with water, after which the sawdust or fiber is mixed in and the resulting mixture is placed in a suitable mold and allowed to harden for about twenty hours. Each core is preferably

formed in a single piece, and, if desired, it may be strengthened by embedding a wire-netting or other light metallic members therein.

In the structure shown in the drawings, A 5 is a core for the door of the nature described above. To this core are secured the facings B and B' of any suitable form, those shown in the drawings comprising the rails a and panels b, which will impart to the door the 10 appearance of the ordinary wooden finish. The edges of the core are also finished by facing-strips c, and these strips are preferably of sufficient thickness to permit of fitting the door to the door-frame and also of setting 15 in the hinges.

D is the core of the door-frame, which is formed of similar material, and is of a size to fit as closely as possible into the opening in the wall. The slight space that may be left 20 between said frame and the edges of the opening in the wall may be filled with cement, mineral wool, or other fire-resisting material, such as d. The exposed faces of this frame are then faced by the jamb-strips, 25 such as E, and the trim F.

A door and door-frame thus constructed will have every appearance of the ordinary wooden door and will harmonize with the rest of the interior finish of the building. At the 30 same time the wooden facings form no part of the essential structure, and in case of a fire may be completely burned off, leaving the door and frame still standing and barring the further spread of the flame, as the material 35 from which the core is made is of a fireproof nature. Its strength and efficiency in resisting the flames are not greatly impaired, no matter what degree of heat it is subjected to.

While I have described the specific structure of a door and door-frame, it is obvious 40 that my invention might be applied to other uses. Again, while I have described wooden

facings I do not desire to be limited thereto, as any material may be used therefor which is suitable for the interior finish of a building and which may be secured to the fireproof core. I shall therefore use in the claims the term "facings of finishing material" as meaning any material suitable for the purpose described. 45

What I claim as my invention is—

1. A fire-resisting structure comprising a core of non-combustible fireproof material and a facing of finishing material, said core being composed of a body of finely-divided compressible material and a binding mineral cement. 50

2. A fire-resisting structure comprising a core of fireproof material, composed of a body of finely-divided fibrous compressible material and a binding mineral cement, said core having glue-adhering surfaces; and a facing of finishing material glued to said core. 55

3. A fireproof structure comprising a single-piece core of non-combustible fireproof material, composed of a body of finely-divided compressible material and a binding mineral cement, and a plurality of facings of finishing material secured to said core. 60

4. A fireproof structure comprising a core of non-combustible fireproof material and facings of finishing material secured thereto, said core being composed of a body of finely-divided compressible and elastic material and a binding mineral cement whereby the resulting substance is of a penetrable tenacious nature adapted to receive and hold nails or screws. 70

In testimony whereof I affix my signature in presence of two witnesses.

ALPHONSE DE MAN.
